MEANS FOR WEB FEED CORRECTION

Robert B. Coffman, Cary, Ill., assignor to Coffman Manufacturing Corporation, Chicago, Ill., a corporation of Illinois

Application March 22, 1949, Serial No. 82,879

6 Claims. (Cl. 271—2.6)

The present invention relates to improvements in the correction of web feed and more particularly relates to the substantial coordination of feed or the rate of feed or travel of a web of material with the operation of apparatus for acting upon or modifying the web or for utilizing successive sections of the web as the web is fed thereto.

As an example of an important use for the present invention candy bar wrapping machines will be referred to, although it will be readily apparent that many other uses can be found for the invention.

In candy bar wrapping machines a printed web or strip of printed paper, foil, cellulose acetate, film, or the like, is fed from a roll or reel of the material to a cut-off mechanism where the web is severed into sections of appropriate length to be wrapped about a candy bar in the further operation of the wrapping machine. Each section of the web has printed thereon, a label which in wrapping up the candy bar must be in proper registration with the article and for this purpose must be substantially centered on the web section or blank.

Due to many variables such as web shrinkage or stretching, machinery lags and tolerances, and the like, overrunning or underrunning of the web sections with respect to the cut-off mechanism is a constant problem.

An important object of the present invention is to provide an improved relatively simple, highly efficient method of and means for controlling the web feed to provide for the delivery of substantially uniform predetermined sections of the web to a point where the web sections are acted upon as by severance from the web.

Another object of the invention is to provide combined electrical and mechanical means for web feed control.

A further object of the invention is to provide an improved web feed control unit which can be conveniently installed for use with an existing machine such as a candy bar wrapping machine.

Still another object of the invention is to provide means which is controlled by variations in travel of the successive predetermined sections of a traveling web to a given point for correcting web travel or feed for substantially eliminating such variations.

Yet another object of the invention is to provide a method of and means for controlling incremental or sectional registration of a traveling web with a given point under conditions which require periodic correction, comprising the continuous subincremental varying of the web feed between periodic corrections.

Other objects, features and advantages of the present invention will be readily apparent from the following detailed description of a preferred embodiment thereof taken in conjunction with the accompanying drawings, in which:

Figure 1 is a diagrammatic and schematic illustration of a web feeding and control system embodying the features of the present invention.

Figure 2 is a side elevational view of the feed correction unit of the present invention.

Figure 3 is a vertical sectional view taken substantially on the line III—III of Figure 2.

Figure 4 is a vertical sectional detail view taken substantially on the line IV—IV of Figure 2.

Figure 5 is a vertical sectional elevation taken substantially on the line V—V of Figure 4.

Figure 6 is a vertical sectional elevation taken substantially on the line VI—VI of Figure 4.

Figure 7 is a vertical sectional elevational view taken substantially on the line VII—VII of Figure 4.

Figure 8 is a vertical sectional view taken substantially on the line VIII—VIII of Figure 4.

Figure 9 is a horizontal sectional detail view taken substantially on the line IX—IX of Figure 4; and

2

chronizing unit adapted for use in the present feed correction system.

In a candy bar wrapping machine, for example, a web 15 of wrapping material is drawn from a supply reel or roll 16 by a set of feed rolls 17 and fed to a severing or cut-off mechanism 18 in which a rotary knife 19 cooperates with a stationary knife 20 to sever the strip or web into sections of proper length for wrapping about a candy bar in the subsequent operation of the machine. The strip or web 15 is printed with a succession of label imprints 21 which are centered or otherwise in predetermined position on the respective sections into which the web is to be severed by the cut off mechanism 18. It is therefore important that feeding of the web 15 be coordinated properly with operation of the cut-off mechanism 18 to effect severance of the web on lines between the successive label imprints 21 so as to have the label imprints on the severed sections in proper position when wrapped about the candy bars or whatever article to which they are to be applied. For visual observance of cut-off registration, the web may be provided intermediate the label imprints 21, as along one margin, with imprinted registration color spots 22. Hence, when the cut-off knives 19 and 20 sever the web in predetermined relation to the registration spots 22, as by cutting through such spots, substantial registration is effected.

According to the present invention, variations from substantial registration of the registration spots 22 at cut-off are automatically corrected in the continuous operation of the machine, and such operation may be at high speed. For this purpose, a feed control unit 23 is drivingly connected with the feed rolls 17 by means such as a sprocket chain 24. The control or correction unit 23 is adapted to accelerate or retard web feed for correctional purposes and is electrically controlled by an electrical control circuit arrangement including a photoelectric cell scanning unit 25 which is appropriately disposed to focus on the margin of the web 15 carrying the registration spots 22. The scanner 25 is included in an electrical control circuit 27 including an amplifier 28 which is in control of a normally open relay switch 29.

In the arrangement shown in Figure 1, an optimum initial adjustment for operation is effected wherein registration of the registration spots 22 with the scanner 25 as the web 15 is fed thereby and the resulting electrical impulses generated by the scanner goes unnoticed by the correction unit 23. For this purpose, the electrical impulses from the scanner 25 while no correction is needed are shunted off to ground by an electrical shunt circuit 30 which prevents amplification of the impulses and closure of the relay switch 29.

In order to afford assurance that feed correction for the web 15 will be made periodically to meet the various factors which might cause either overrun or underrun of the web in operation, provisions are made for positive overrun or underrun of the web by small increments with respect to registration of the registration spots 22 with the cut-off 18 and then positive correction at periodic intervals as the successive registration spots vary to a predetermined limit out of the preferred optimum registration with the cut-off. For example, an incremental lag relationship is shown in Fig. 1 wherein as successive sections of the web 15 are cut off the web gradually lags until the permissible limit of variation from the optimum registration occurs and at which time a normally closed switch 31 in the shunt circuit 30 is opened in synchronism with the registration of one of the registration spots 22 with the scanner 25 and the resulting generation of an electrical impulse by the scanner.

As a result, such impulse is amplified and effects energization and closing of the relay switch 29 and closing of an energizing circuit 32 for a correction solenoid 33 which is energized to operate the correction unit 23 which functions to overdrive the feed roll assembly 17 sufficiently for one revolution to compensate for the lag in the web 15 and thus readjust the web to the initial optimum registration relationship of the registration spots 22 with the cut-off 18 or even slightly in advance of such optimum adjusted relationship. Promptly upon completion of the correctional adjustment of the traveling web 15 a normally closed reset switch 34 is opened to break a control circuit 35 for

the relay switch 29 and thus effect deenergization and opening of the switch 29 and resulting breaking of the solenoid circuit 32, deenergization of the solenoid 33 and return of the control unit 23 to its interim condition or relationship in the system.

In one practical form, the synchronizing switch 31 and the resetting switch 34 may form part of a switch assembly unit 37 (Fig. 10), in which the switches are disposed on respective opposite sides of a shaft 38 which may be any shaft that is part of the machine with which the web controlling and correction system is associated and which rotates in some predetermined relationship or ratio to a shaft 39 carrying the rotary cut-off blade 19 (Fig. 1). The rotation ratio of the shafts may be one to one. A control cam 40 carried by the shaft 38 has a lobe 41 engageable once in each revolution of the shaft with followers on respective switch arms 42 and 43 disposed 180° apart. Through this arrangement the cam lobe 41 alternately deflects the switch arms 42 and 43 from the closed switch position into which the arms are normally biased by suitable spring means. Thus, each of the switches 31 and 34 will be opened momentarily once in each full revolution of the shaft 38 and the switch openings will occur successively, and with a time interval determined by one-half revolution of the shaft 38. The switch unit 37 may be equipped with appropriate attachment bracket structure 44 by which it can be secured in service position on a convenient frame portion of the associated machine.

Both incremental lag in the web feed and correctional overdrive are effected by the correction unit 23 which is in the form of compact unit mounted on or in association with a mounting panel or plate 45 (Fig. 2), which is adapted to be secured in an appropriate location on the frame of the machine with which the present web feed correction system is used. On the mounting plate 45 is secured the solenoid 33. A shaft 47 which may be either a stub shaft coupled onto a shaft of the machine or may be a shaft of the machine rotating in operation in preferably one to one ratio with the cut-off shaft 39, extends through a bearing aperture 48 in the mounting plate 45 and projects to a substantial extent beyond the outer face of the plate (Fig. 4). Rotatably mounted on the shaft 47 is drive means such as a sprocket 49 about which the web feed drive chain 24 is trained.

Means are provided for coupling the sprocket 49 for co-rotation with the shaft 47 and also for a relative over-run rotation or under-run rotation, as desired. To this end, the sprocket 49 has a tubular stub shaft 50 concentrically bearinged about the drive shaft 47 for free relative rotation and extending inwardly along the drive shaft. At its inner end, and in spaced relation to the sprocket 49, the stub shaft 50 has fixedly thereon a toothed ratchet wheel assembly 51 which is preferably made up of a plurality, herein shown as three, ratchet disks having the teeth progressively incrementally offset for fine incremental ratcheting interconnection with a complementary set of coaxially pivoted, identically formed, relatively rockable pawls 52, one for each of the ratchet plates of the ratchet wheel assembly 51. The pivot for the pawls 52 is provided by a pin 53 (Fig. 7) fixedly carried by a drive disk 54 which is keyed on otherwise fixedly secured to the drive shaft 47. The relationship of the ratchet wheel assembly 51 and the pawls 52 is such that in the counterclockwise rotation of the shaft 47 as viewed in Figs. 2 and 7, the drive disk 54 through the medium of the pawls 52 drives the ratchet wheel assembly 51 and thus drives the sprocket 49 rotatably with the shaft 47.

By proper selection of the sprocket 49 proper ratio is provided with respect to the feed roll assembly 17 to provide for an underfeed of the web 15 to the cut-off mechanism 18. After a certain number of driving revolutions of the shaft 47 and thus feeding of a certain number of sections of the web 15 through the cut-off 18, a correction is called for by the scanner circuit as explained hereinabove, and the solenoid 33 operated. As a result, the solenoid draws a connecting link 55 toward the left as viewed in Fig. 2 from the full line position to the dot-dash position and rocks a rock lever 57 pivotally mounted on a stub shaft 58 carried by the mounting plate 45. The rock lever 57 is connected as by means of a universal ball joint 59 with a link 60 which is pivotally connected as at 61 with an ear 62 at one edge of an eccentric slide plate 63. Opposite longitudinal beveled edges 64 on the plate 63 are slidably engaged in complementary bearing tracks provided by gib plates or bars 65 removably secured to the mounting plate 45 and providing a generally dove tail track or way for the eccentric plate 63. Thus, in rocking of the rock lever 57 by the solenoid 33, the eccentric plate 63 is correspondingly shifted as indicated, from the full line to the dash line position in Fig. 2.

Shifting of the eccentric plate 63 causes a rotary disk 67 peripherally rotatably bearinged in a complementary central bearing hole 68 in the plate to be moved into predetermined eccentric relation to the shaft 47 which the disk 67 clears by means of an axial clearance aperture 69 of large enough diameter to afford a substantial range of eccentric movement of the disk with the eccentric plate 63 relative to the shaft 47. The disk 67 is connected by means of a pin 70 to one end portion of a control bar 71 (Figs. 6 and 9) which is reciprocably slidably assembled within a diametric groove or way 72 recessed in the face of the drive plate 54 which opposes the eccentric plate 63. A longitudinal slot 73 in the control bar clears the shaft 47.

The opposite end portion of the control bar 71 projects substantially beyond the periphery of the drive disk 54 and has a right angularly outwardly extending head flange 74 (Figs. 3 and 4) of a length to extend outwardly beyond the ratchet assembly 51 and opposite the space between the sprocket 49 and the ratchet wheel assembly. Secured to the outer end portion of the head flange 74, as by means of a screw 75 is a stem 77 secured as by means of a threaded assembly with one end of a rack frame 78 internally dimensioned to clear the hollow stub shaft 50 therethrough and also to afford clearance for a pinion 79 carried by a transmission disk 80 which is slidably interposed between the rack frame 78 and the outer side of the ratchet wheel assembly 51 and is freely rotatably bearinged on the stub shaft 50 (Figs. 4, 8 and 9). For convenience in assembly one side of the rack frame 78 is equipped with a detachable rack bar 81. Play or sloppiness in meshing of the teeth of the pinion 79 and the rack bar 81 is avoided by a tension spring 82 connected therebetween as best seen in Fig. 8.

The disk 80 is of larger diameter than the ratchet wheel assembly 51 and on its inwardly facing margin the plate carries a set of pawls 83 (Figs. 7 and 9) which are preferably identical with the pawls 52 and interengage with the ratchet disks of the assembly 51 on the diametrically opposite side of the ratchet assembly. Pivot for the pawls 83 is provided by a pin 84 carried by disk 80. Identical, multi-finger leaf springs 85 carried by respectively the drive disk 54 and the transmission disk 80 provide resilient ratcheting bias for the sets of pawls 52 and 83, respectively.

Protective enclosure for the transmission assembly is afforded by a casing tube 87 carried fixedly peripherally by the drive disk 54 and in turn carrying an outer closure plate 88. An aperture 89 in the casing tube 87 affords clearance for the rack frame stem 77. An axial aperture 90 in the closure plate 88 affords free rotary clearance for the stub shaft 50.

In operation of the web feed correction unit 23, the eccentric plate 63 is initially adjusted for the particular web being fed through the associated machine by manipulation of a turn buckle type of adjustment thumb screw 91 (Figs. 2 and 3) in the connecting link 60, if necessary, for predetermined fixed eccentricity of the rotary eccentric disk 67 with respect to the drive shaft 47 to effect advance of the web 15 at a rate incrementally out of phase or synchronism with proper or optimum registration of the sections 21 with the cut-off 18. As the shaft 47 rotates and carries with it the fixed drive disk 54, the slide member 71 is carried with the disk 54 and through the pin connection 70 turns the eccentric 67. By reason of the eccentric connection afforded by the pin 70, it will be apparent, the slide member 71 will be reciprocated in its track 72 in the drive disk 54 in each revolution of the shaft 47. As the member 71 reciprocates it carries with it the rack frame 78 and correspondingly rotates the pinion 79 and thereby the transmission disk 80. As the rack frame 78 moves on its out-stroke so that the transmission disk 80 is turned clockwise as viewed in Figs. 7 and 8, the pawls 83 are carried counter the rotation of the shaft 47 to the adjusted extent determined by the eccentricity of the disk 67 in the plate 63. As the rack frame 78 moves on its in-stroke, the pinion 79 and the transmission plate 80

rotate in overrun relation to the shaft 47 and the pawls 83 act to turn the ratchet assembly 51 and thereby the stub shaft 50 and the sprocket 49 to the same extent, thus effecting an overdrive of the feed mechanism 17. This relationship is desirable where due to various factors the incremental lag in feed of the web 15 will not work out properly for the particular coordination predetermined in the correction system as a whole to warrant one to one or concentric disposition of the eccentric plate 63. Hence, constant feed lag with partial web feed correction in each cycle and a small incremental under correction that eventually accumulates after several cycles into a total lag requiring operation of the electrical system for a full web feed correction is provided. For example, adjustment may be such as to require a full correctional feeding overdrive on every eight to ten cycles or revolutions.

When the scanner 25 signals that the registration spots are running far enough behind the optimum registration desired with relation to the cut-off 18 to warrant full correctional overdrive, and the solenoid 33 is energized to effect maximum eccentricity of the eccentric plate 63, corresponding overdrive of the sprocket 49 is effected by the overdrive transmission. Deenergization of the solenoid 33 upon completion of the web feed correction releases the eccentric plate actuating linkage for return to the non-eccentric, or minor adjusted eccentric condition of the eccentric plate 63. Quick return of the actuating linkage is provided for by resilient biasing means such as a coiled tension spring 92 (Figs. 2 and 3) connected between an anchor pin 93 on the mounting plate 45 and the rock lever 57.

The extent of the throw or operative rocking of the lever 57 is adapted to be adjusted by means of a stop screw 94 threadedly carried by a boss 95 and opposing return throw of the rock lever 57 under influence of the return spring 92. A lock nut 97 holds the stop screw 94 in adjusted position.

In order to facilitate a resetting of the correctional unit 23 for known conditions, a calibrated adjustment scale arrangement 98 is provided on the margin of the eccentric plate 63 and one of the track bars 65.

Although the correctional unit 23 has been shown in specific detail for overdrive correctional action, it is obvious that an underdrive correctional operation thereof can be readily provided for by simple changes involving merely reversal of certain parts.

It will, of course, be understood that various details of construction may be varied through a wide range without departing from the principles of this invention and it is, therefore, not the purpose to limit the patent granted hereon otherwise than necessitated by the scope of the appended claims.

1. In apparatus including a rotary shaft, a web feed correction unit, a mounting plate having accommodation for operation of said rotary shaft therethrough, an eccentric plate slidably mounted on said mounting plate and having a disk rotatably supported thereby with its axis shiftable from concentricity with said shaft to an eccentric relation to the shaft by sliding shifting of said eccentric plate, a rotary member having bearing relation to the shaft enabling relative rotation of said rotary member, means for normally coupling the rotary member for joint rotation with the shaft, and means including a member coupled with said rotary disk and operable reciprocably relative to said shaft when said eccentric plate is moved to shift the axis of the disk to eccentricity relative to the shaft for acting upon said rotary member to drive the same rotatably relative to the shaft while the rotary member is rotating with the shaft.

2. In apparatus including a rotary shaft, a web feed correction unit, a support to be disposed in operative relation to said rotary shaft, a shiftable eccentric plate carried by the support and having a disk rotatably supported thereby with its axis shiftable from concentricity with said shaft to an eccentric relation to the shaft by shifting of said plate, a rotary member to be carried by the shaft and having bearing relation to the shaft enabling relative rotation of said rotary member, means normally coupling the rotary member for joint rotation with the shaft, means for adjusting the position of said eccentric plate for determining the eccentricity of said rotary disk, and means connecting said disk with said shaft and with said rotary member for cyclical incremental rotation of

said rotary member relative to the shaft as governed by the eccentricity of the disk relative to the shaft.

3. In combination an apparatus for controlling a web feeding mechanism, a rotary drive member having a hollow shaft adapted to be relatively rotatably received upon a continuously rotating shaft, a ratchet wheel device carried by said hollow shaft in spaced relation to said rotary member, a drive coupling member adapted to be fixedly secured to the rotary shaft in face to face relation with the ratchet wheel device, pawl means effecting a coupling between the coupling member and the ratchet wheel device for joint rotation of the members, a transmission disk rotatably carried by said hollow shaft and having pawl connection with said ratchet wheel device, a pinion carried by said disk, a rack disposed in meshed relation to said pinion, and means for selectively reciprocating said rack to actuate said pinion and disk and rotate said ratchet device and hollow shaft and drive member relative to said coupling member.

4. In combination an apparatus for controlling a web feeding mechanism, a rotary drive member having a hollow shaft adapted to be relatively rotatably received upon a continuously rotating shaft, a ratchet wheel device carried by said hollow shaft in spaced relation to said rotary member, a drive coupling member adapted to be fixedly secured to the rotary shaft in face to face relation with the ratchet wheel device, pawl means effecting a coupling between the coupling member and the ratchet wheel device for joint rotation of the members, a transmission disk rotatably carried by said hollow shaft and having pawl connection with said ratchet wheel device, a pinion carried by said disk, a rack disposed in meshed relation to said pinion, and means for selectively reciprocating said rack to actuate said pinion and disk and rotate said ratchet device and hollow shaft and drive member relative to said coupling member, said rack reciprocating means including an angular member reciprocably carried by said coupling member.

5. In combination in a web feed control unit, a pair of rotary members mounted for rotary operation in unison and differentially, clutch mechanism effecting connection between said rotary members for said unison rotation and including means for effecting differential rotation of said rotary members during unison rotation of the members, said means including a member reciprocable transversely relative to said rotary members and rotatable in unison therewith, a non-rotary reciprocable member having thereon a rotary crank device coupled with said rotary and reciprocal member and operable by reciprocal shifting of said non-rotary reciprocal member to effect predetermined reciprocal movement of said reciprocal and rotary member for actuating said clutch mechanism to cause differential rotary movement of said rotary members.

6. In combination in a web feed control unit, a supporting structure, a member guided for reciprocal movement on said supporting structure, a member rotatably supported by said reciprocably supported member, a pair of rotary members rotatable in unison and differentially, clutch means connecting said rotary members for said unison and differential rotation, and means for controlling operation of said clutch means including a crank connection with said rotatably mounted member on said reciprocal member, said reciprocal member being movable in a fixed reciprocal path to alter the crank operation on said control means.
